[57] CLAIM

The ornamental design for a hanger for skirts, slacks or trousers, as shown and described.

DESCRIPTION

FIG. 1 is a front elevational view of a hanger for skirts, slacks or trousers showing my new design, the rear being a mirror thereof;

FIG. 2 is a side elevational view taken from the right of FIG. 1 in the closed position;

FIG. 3 is a side elevational view taken from the right of FIG. 1 in the open position.

FIG. 4 is an enlarged prospective view taken at an angle, of the fastener element of my design, in a substantially closed position.
